UNITED STATES PATENT OFFICE.

OSCAR L. GLASER, OF OAK PARK, ILLINOIS, ASSIGNOR OF ONE-HALF TO JOHN F. BLYTHING, OF OAK PARK, ILLINOIS.

SAFETY RAZOR.

1,423,414.

Specification of Letters Patent. Patented July 18, 1922.

Application filed July 10, 1919. Serial No. 309,880.

To all whom it may concern:

Be it known that I, OSCAR L. GLASER, a citizen of the United States, residing at Oak Park, in the county of Cook and State of Illinois, have invented certain new and useful Improvements in Safety Razors, of which the following is a specification.

The invention relates to improvements in safety razors.

10 One of the objects of the invention is to provide a yielding connection between the blade holder, or head, and the handle of a safety razor, whereby to make the operation of the razor more efficient and comfortable 15 to the user.

The invention may take the form of an attachment which may be introduced at any time between the major parts of razors already in existence so that razors of standard type may be furnished with the attachment.

20 Another object of the invention is to provide an attachment consisting of a spring having threaded terminals for introduction 25 between the blade-holding head and the handle and which cooperate with the threaded portions of these members.

Other and further objects of my invention will become readily apparent to persons 30 skilled in the art, from a consideration of the following description when taken in conjunction with the drawings, wherein:

Fig. 1 is an elevation showing part in section, taken on line 1—1 of Fig. 2, of a 35 well known type of safety razor with my attachment inserted between the head and the handle thereof.

Fig. 2 is an elevation of the device at right angles to Fig. 1.

40 Fig. 3 is a perspective view of the attachment.

In all the views the same reference characters are employed to indicate similar parts.

45 The head A of the razor comprises a blade-holding part 5, provided with a threaded stud 6 that projects through the blade 7 and through the guard 8. The threaded stud 6 usually extends into a 50 threaded opening 9, of the socket 10 secured on the end of the handle B.

My improvement consists of the part C

which comprises a substantially U-shaped spring 11, made, preferably, of spring steel and properly tempered, provided with a 55 threaded stud 12, similar in character in every respect to the stud 6, for insertion in the threaded opening 9 of the socket 10. On its other end it is provided with a nut 13, screw threaded, as at 14, for insertion 60 on the stud 6 of the head 8.

To insert the cushioning device C between the head and handle of the razor it is only necessary to unscrew the handle so that the stud 6 is removed from the threaded socket 65 9 in the handle and then the stud 6 is screwed into the nut 13 and the stud 12 is screwed into the threaded socket 9, as shown in Fig. 1.

The elasticity of the spring 11 should be 70 graded in accordance with the harshness or softness of the beard of the person using the instrument. Persons having a soft beard and tender face that is easy to shave, may, advantageously, use a spring of very 75 light elastic strength, while persons having a harsher and a more stubborn beard should use a stiffer or stronger spring.

The result produced by the effect of the spring is very pronounced and satisfactory, 80 making the act of shaving much more comfortable than when the blade-holding head is rigidly attached to the handle.

Having described my invention, what I claim is:

1. An attachment for a safety razor which has a relatively rigid blade holder and a relatively rigid handle, comprising a substantially U shaped spring member one leg 90 of which is attachable against the blade holder to carry the same and the other leg of which is attachable against the end of the handle.

2. A safety razor comprising a relatively rigid blade holder having a threaded stud, 95 a relatively rigid handle having a threaded socket, a resilient substantially U shaped member having a threaded socket to receive the stud of the blade holder, and a threaded stud for securing said member to the handle. 100

In testimony whereof I hereunto subscribed my name.

OSCAR L. GLASER.
